BANK FIXTURE

Application filed May 18, 1929. Serial No. 364,244.

Our invention relates to bank fixtures, and more particularly to bank counters and to protective means associated with such counters. Banks and financial institutions are generally provided with "cages" for the individual tellers and bank operators with whom customers and business people transact their business. These cages are generally four walled enclosures, each cage having a self-closing and self-locking door. In localities where space is valuable and floor room is limited, these cages present serious objection due to the large amount of floor space required for each. These cages must furthermore be spaced a considerable distance from the building wall to the rear thereof to provide the necessary passageway to and past the cages. Cages comprising four wall enclosures, with self-closing and self-locking doors, have generally been considered necessary in order to provide the proper protection to the securities and valuables contained therein. Tellers, when temporarily leaving the cages, usually leave their currency, papers, etc., on top of the counters, relying solely on the locked cage doors to protect these articles against confusion and loss, since it is very tedious and time-consuming to take these articles from the counter and lock them in a drawer whenever a cage is vacated temporarily, and to restore them from the drawers to the counters each time a teller returns. Also, such handling of these articles leads to confusion and loss. Because the tellers leave their articles on the counters when temporarily leaving the cage, it is unexpedient for a substitute or temporary teller to do business in another teller's cage, due to the likelihood of confusion of papers, currency, records and the like.

An object of this invention is to provide a counter over which a customer can transact business readily and easily with a teller or bank operator, and which eliminates the necessity of having teller's cages.

Another object of this invention is to provide a counter for banks and other financial institutions adapted to safeguard and protect the teller's currency, papers, and other ar-

ticles against confusion, loss and burglary without requiring a cage for this purpose.

Another object of this invention is to provide a counter adapted for use in banks and financial institutions generally, which permits a temporary teller to occupy and transact business at any counter without danger of confusion of currency, papers or the like of the temporary teller with the currency, papers or the like of the teller regularly stationed there.

A further object of this invention is to provide a teller's counter for banks and financial institutions adapted to supplant the cage compartments generally in use; which gives added protection against robbery, loss and confusion; which occupies little space; which lends itself readily to aesthetic harmony with the bank interior; which can be easily and quickly installed; which is easy to keep clean and sanitary; and which can be manufactured and supplied at less cost than the cage compartments now generally in use.

Other objects of this invention will become obvious as the disclosure proceeds.

In accordance with our invention, our fixture comprises usually a line of tellers' counters positioned along the partition or wall which the customers approach to transact business with the tellers, these counters being preferably well below the windows through which the business is transacted. As usual, at the bottom of each window is a shelf on which articles are placed when passed between the teller and customers. Inside the partition and below the transacting shelves are working counters for the tellers. A characteristic of our invention is the provision of a cover for each work counter, whereby articles on each counter are protected against confusion, loss and robbery. The cover may be designed to cover any part or the whole of the counter, as desired. Each cover is capable of ready and easy manipulation by the teller at the counter and is preferably self-locking. Also, preferably, means are provided whereby any teller or a person at a remote point, may, by a simple operation, cause all of the covers to cover and become locked over all of

the working counters. This feature is extremely valuable as a protection against robbery by hold-up methods during hours when the currency and papers are exposed on these counters. Preferably, the covers are hidden from the view of a person standing at a teller's window. The individual working counters are preferably separated by small partitions which have guides for the covers and house the closing mechanism.

In order that a clearer understanding of our invention may be had, attention is hereby directed to the accompanying drawings forming a part of this application and illustrating certain possible embodiments of our invention.

Referring to the drawings, Figure 1 is a rear view of our bank fixture;

Figure 2 is a cross-sectional view of our bank fixture and is taken on line 2—2 of Figure 1;

Figure 3 is an enlarged fragmentary cross-sectional view taken transversely across our bank fixture, certain parts being broken away to show more clearly certain features thereof, this view being taken on line 3—3 of Figure 1;

Figure 4 is an enlarged fragmentary cross-sectional view taken longitudinally along our bank fixture, showing particularly certain parts of the mechanism for operating the roll top closures, this view being taken on line 4—4 of Figure 3;

Figure 5 is an enlarged fragmentary vertical cross-sectional view of our bank fixture showing more particularly the latch device automatically operative to lock the roll top closure against movement when moved into closed position, this view being taken on line 5—5 of Figure 6;

Figure 6 is an enlarged fragmentary vertical cross-sectional view showing a portion of the roll top closure with its associated latch device, this view being taken on line 6—6 of Figure 5;

Figure 7 is an enlarged vertical cross-sectional view through the lower edge of the roll top closure, showing particularly the handle construction by means of which the roll top closure may be manipulated, this view being taken on line 7—7 of Figure 1;

Figure 8 is an enlarged vertical cross-sectional view showing the foot pedal and associated electrical contact switch by means of which all the latch bolt solenoids may be operated to retract the latch bolts, permitting the roll top closures to move into closed position, this view being taken on line 8—8 of Figure 1;

Figure 9 is a diagrammatic view of the various circuit connections for operating the pair of latch bolts in each teller's compartment, two of the individual switches in separate tellers' compartments being shown closed and the latch bolts retracted; and

Figure 10 is a similar diagrammatic view

showing the circuit connections for operating all the latch bolts within all compartments simultaneously, one of the switches conveniently positioned somewhere in the bank being shown closed, this switch being operative to retract all of the latch bolts so that all the roll top closures will move into closed position.

Similar reference characters refer to similar parts throughout the several views of the drawings.

Referring to the drawings, the longitudinal partition 11, surmounted grating 17, or windowed extension, and customer's shelf 13, may be of any usual construction, shelf 13, preferably extending an appreciable extent inwardly of the partition 11. A ledge or shelf 12, for the general convenience of customers, extends substantially the full length of the partition 11.

A plurality of transverse partitions 14, of suitable height, are secured along one edge to the longitudinal partition 11 and are spaced apart a convenient distance to define individual spaces or compartments for the tellers. It will be understood that the longitudinal partition 11 can be located and arranged as desired within the bank interior, and as many teller spaces may be provided as necessary to care for the business of the bank. The transverse partitions 14 may be of any length desirable and convenient for the particular location. Preferably, to economize space, the partitions 14 do not extend back of the working shelves or counters 15, which extend between the transverse partitions below the customer's shelves 13. If desired, a drawer 16 may be mounted beneath each work shelf.

In order that the teller or bank operator may properly protect the securities and valuables of which he is placed in charge, we provide a roll top closure which may be closed and locked over each working counter 15. This roll top closure is designed to afford all the protection and safety which a four-walled caged compartment having a self-closing and self-locking door provides. Each roll top closure comprises a plurality of narrow strips or sections 18 hinged together at their flange portions 19 in a well-known manner, as shown in Figure 3. These hinged sections are preferably made of strong and durable metal. It is understood that a roll top closure is provided for each teller's working counter, and extends the full width thereof.

To direct the movement of the roll top closure, we preferably provide a pair of channel shaped guide members 20, one of the guide members being fixed to or positioned within a recess provided in the inside face of each transverse partition forming the side walls of the teller's space. Each guide member 20 is preferably arch shaped in longitudinal outline, as shown in Figure 3, so as to direct the roll top closure along the inside face of the longitudinal partition 11, along the under

face of the counter 13, and then downwardly from the customer's shelf to the working counter 15. The roll top closure will occupy little space and will be completely out of the way when fully raised. Each guide member is provided with a lip portion 21, which forms a track, as shown in Figure 4, along which the side edges of the roll top closure are adapted to ride.

10 It is essential that means be provided for moving the roll top closure from open to closed position and vice versa, with ease and facility requiring the least possible effort and time. With this in view, we provide a counter-weight arrangement associated with each roll top closure for automatically moving the roll top closure from open to closed position when it is free to do so. A suitable weight 22 is connected by means of a chain or cord 23 to each end and to the front edge of each roll top closure, as shown more particularly in Figures 3, 4 and 5. Each transverse partition 14 is preferably hollow so as to house two counter-weights and associated connecting chains. As shown in Figures 3 and 4, two sets of vertical angle irons 24 are provided in each partition to form guideways for the counter-weights. Four angle irons may form the guideway for a single counter-weight, each engaging a vertical edge of the counter-weight.

15 The front edge of the roll top closure is preferably provided with an edge bar 25, as shown more particularly in Figures 3 and 6. This edge bar is preferably of channel shape, one leg of the channel being secured directly to the adjoining hinged section 18' of the roll top closure. A lug 26 projects from each end of the edge bar to a counter-weight chain 22 which may be secured to these lugs. Each pair of counter-weights are so weighted that they will normally operate to pull the roll top closure to closed position. A heavy edge bar 27 may be secured to the rear hinged section of each roll top closure, as shown more clearly in Figure 3, to strengthen the rear edge thereof and to balance the effects of the counter-weights 21.

20 Means are provided to prevent binding of the roll top closure in the guide members, and to insure uniform and smooth operation thereof. To this end, we provide a pair of discs 28 having notches 29 cut in the peripheries thereof, which are adapted to receive the flanged edges 19 of the sections 18 comprising the closure. The notched discs 28 are positioned close to the compartment side walls, and are preferably mounted on and secured to a shaft 30 which extends the width 25 of the compartment. Each end of the shaft 30 is journalled in a suitable journal block 31 fixed to a side wall partition. The notched discs and connecting shaft are preferably located well under the shelf 13, so as to be out 30 of the way. It is understood that the notched

discs are so positioned as to engage with the flanges 19 of the respective closure sections, and since both discs are fixed to the shaft they move in unison and thus maintain the sections in parallel alignment at all times, so that no binding action of the roll top closure can take place.

25 A cushioning strip 32 may be provided in the top of the working shelf 16 against which the front edge bar 25 of the roll top closure may seat when the roll top closure is in closed position. This strip, however, may be omitted if the counter is covered with linoleum.

30 Means are provided to automatically lock the roll top closure immediately upon its arrival in closed position. We provide a rocking block 33 pivotally mounted within the channel shaped edge bar 25, shown more particularly in Figures 5 and 6. A slide rod 34 is connected at one end thereof to each end of the rocking block. These rods extend in opposite directions and are slidably supported by suitable guide blocks 35. The free end of each slide rod is provided with a stud portion 36, which is adapted to seat within a suitable hole or recess provided in each guide member 20. A compression spring 37 encircles each slide rod and is retained between one of the guide blocks 35 and an abutment collar 38 secured to the slide rod. Each coil spring normally tends to project the slide rod on which it is mounted in an outward direction. As soon therefore as the stud portion at the outer end of each slide rod is opposite the corresponding recess in the guide member 20, the stud portion will immediately project thereinto, locking the roll top closure in closed position. Each teller is provided with a key (not shown) adapted to be inserted into a suitable lock 39 operable to rock or rotate the rocking block 33 so as to retract the stud portions 36 from the recesses provided in the guide members. It is now seen that as soon as the roll top closure is moved into closed position, the same will be automatically locked in closed position. Slide rods 34 can only be retracted and the roll top closure moved to open position when the authorized key is inserted into the lock. Each teller is charged with the care of his own key, and he alone therefore can open the roll top closure in his compartment.

35 To facilitate the opening of the roll top closure, we preferably provide a pair of hand grips 40 which can be easily grasped by the teller. As shown in Figure 7, each handle may be made by providing a recess, in the front edge bar, so shaped as to conform to the human hand. Since the edge bar 25 is preferably made of heavy metal, these handles may be formed integrally therewith by stamping or casting the bar so as to provide these handle recesses in the front side wall thereof.

The shelf 13 preferably extends some distance beyond the path of movement of the roll top closure. The overhanging portion 41 prevents the roll top closure from being visible to anyone stationed outside of the teller's counter. Unless a person entering the bank has previous knowledge of the roll top closure, he will have no way of knowing that the teller's counter is so equipped. This is of advantage when the teller is confronted with burglars, for example. The under side of the overhanging portion of the counter may be recessed, as shown in Figure 3, and illuminating means such as an electric light bulb 42 may be positioned within the recess. A reflector 42' may be placed in the bulb receiving recess which will diffuse the light emanating from the electric light bulb uniformly over the entire top portion of the working shelf. Means are provided to releasably retain each of the roll top closures in open position. An opening is cut in the customer's counter directly over each transverse partition, as shown more clearly in Figures 3 and 4. A pair of latch bolts 43 are vertically mounted within suitable brackets secured within each opening. Each bracket may comprise an attaching portion 44 and spaced collar portions 45 within which the latch bolt is adapted to slide. An expansible coil spring 46 may be placed over the upper end of each latch bolt and held in place thereon by a suitable cap 47 secured to the collar portion 45 of the bracket. The coil spring 46 normally operates to shoot its latch bolt downwardly. If the roll top closure has been completely opened so that the front edge thereof is positioned to the rear of the latch bolt, the coil spring associated therewith will operate to shoot the latch bolt downwardly and prevent downward closing movement of the roll top closure. The roll top closure can thus be retained indefinitely in open position. A cover plate 48 which lies flush with the top surface of the counter and is removably secured thereto, may be provided to cover each hole cut in the counter.

An electrical device is provided by means of which the teller may retract the latch bolts conveniently and with little effort, so as to permit his roll top closure to move into closed position. A solenoid 49 may be associated with each latch bolt. The solenoid is positioned between the collar portions 45 of the supporting bracket and surrounds the latch bolt 43. The latch bolt thus forms, in effect, the core of the solenoid. A vertical slot may be cut in each latch bolt into which slot the end of a set screw 50 may extend to prevent the latch bolt from rotating. It is clear that by energizing the solenoid the latch bolt constituting the core piece thereof will be drawn upwardly, so that the lower end of the latch bolt will be moved out of engagement with

the roll top closure, permitting the roll top closure to be moved into closed position by its counter-weights.

Each pair of solenoids are connected in a suitable electric circuit. Referring more particularly to Figure 9, a power source, such as a storage battery 51, is provided. A switch 52 is conveniently located in each teller's compartment. Closing of this switch by the teller will automatically operate to retract the pair of latch bolts which maintains in open position the roll top closure within his compartment. This switch may comprise an ordinary button switch normally maintained in out-of-contact position by a suitable spring device 52'. When the button switch in compartment A is closed, for example, current flows from the battery 51 through conductor 53, through solenoid 49 positioned at one end of the roll top closure, through conductor 54, through the switch 52, through conductor 55, through the solenoid 49 positioned at the other end of the roll top closure, through conductor 56, through main line conductor 57, and back to the battery. As soon as the latch bolts are retracted, counter-weights 22 will pull the roll top closure into closed position. It is seen that by means of this circuit arrangement the teller is able to close the roll top closure over his counter by merely pressing the push button switch, and without disturbing the roll top closures of any other teller.

If the teller in compartment C, for example, desires to close his roll top closure, he merely presses the push button switch 52 located within his compartment. Current from the battery 51 will then flow through conductor 53, through conductor 58, through conductor 59, through one of the solenoids 49, through conductor 60, through compartment switch 52, through the conductor 61, through solenoid 49 located within compartment C, through conductor 62, through main line conductor 57 and back to the battery. It is seen that by this arrangement each teller may close his roll top closure with ease and facility, and without disturbance of the closures located over any other counter.

The switches in compartments B and D, for example, are shown open and no current therefore flows through the latch bolt operating solenoids 49 located therein. The circuit from the battery through the latch bolt operating solenoids located in compartment B comprises conductor 53, conductor 58, conductor 63, one of the solenoids 49, conductor 64, the switch 52, conductor 65, the other solenoid 49, conductor 66 and main line conductor 57. The circuit connection from the battery through the latch bolt operating solenoids located in compartment D similarly comprises conductor 53, conductor 58, conductor 67, one of the solenoids 49, conductor 68, the switch 52, conductor 69, the other sole-

noid 49, conductor 70 and main line conductor 57.

In case of holdups and bank robberies it is desirable to provide means whereby all of the 5 roll top closures can be closed from various spaced points in the bank. This becomes evident when it is realized that robbers often prevent any protective action being taken by the teller whose compartment they are planning to rob. To this end, we provide an arrangement whereby a person who is free to act may automatically close all of the roll top closures over all of the counters at once, so as to prevent the robbers from gaining access to the securities and valuables on any of the counters. To this end, we provide a foot 10 pedal switch located, for example, in the floor at each teller's compartment by means of which any teller, who is free to act, may move 15 into closed position all of the roll top closures located in the various tellers' compartments. It will be understood, however, that these foot pedal switch devices may also be variously located in the bank where they 20 could readily be operated by anyone not under the immediate control of the robbers.

We have shown in Figure 8 a preferred form of foot pedal switch, which may be located in the floor of the bank. A cavity may 25 be cut in the floor and a suitable cover member is positioned thereover. The foot pedal switch comprises a stem portion 71 and a head portion 72. The cover member comprises a cover portion 73 and a guide collar portion 74 through which the stem portion of the foot pedal extends. The cover member may be secured to the floor in any suitable manner, as by screws 75. The lower portion 76 of the stem 71 may be of reduced cross section. An expansible coil spring 77 surrounds the reduced portion 76 of the stem and is retained between the shoulder portion 78 thereof and the lower wall 79 of the cover member. The coil spring normally tends to 30 project the foot switch upwardly. A metallic contact collar 80 is suitably secured to the lower end of the stem portion of the foot switch as by clamping the same between a plate 81 and a nut 82 carried by the stem portion. Suitable insulation 83 may be provided separating the contact collar 80 from the stem 71.

An insulating block 84 located below the foot switch may be secured within the hole 35 in the floor by a screw 85. The insulating block carries a pair of contact points which may comprise ordinary iron bolts 86 suitably secured thereto. The wires or conductors leading thereto may be contained within a suitable piping 87 embedded within the floor.

Referring now more particularly to Figure 10, let it be assumed that the foot pedal switch located in teller's compartment A is closed. Closing of this foot pedal switch will 40 automatically retract the latch bolts in all

the compartments, whereupon the counterweights will pull all of the roll top closures into closed position. When the foot switch in compartment A is closed, for example, current will flow from the battery 51, through conductor 53, through one of the solenoids 49 in compartment A, through conductor 54, through conductor 88, through the foot switch 72, through conductor 89, through conductor 55, through the other solenoid 49 in compartment A, through conductor 56, through main line conductor 57 and back to the battery, thus retracting the latch bolts associated with the solenoids in compartment A and causing the roll top closures in compartment A to close.

Closing of the foot switch in compartment A will also close the circuit between the battery and the latch retracting solenoids located in compartment B. With the closing of the foot switch in compartment A current flows from the battery 51, through conductor 53, through conductor 58, through conductor 63, through one of the solenoids 49 in compartment B, through conductor 64, through conductor 90, through conductor 91, through the foot switch 72 in compartment A, through conductor 92, through conductor 93, through conductor 65, through the other solenoid 49 in compartment B, through conductor 66, through main line conductor 57 and back to the battery, thus retracting the latch bolts in compartment B and permitting the roll top closure therein to move into closed position. In like manner current will flow from the battery 51 through conductor 53, through conductor 58, through conductor 59, through one of the solenoids 49 in compartment C, through conductor 60, through conductor 94, through conductor 91, through the foot switch 72 in compartment A, through conductor 92, through conductor 95, through conductor 61, through the other solenoid 49 in compartment C, through conductor 62, through the main line conductor 57, and back to the battery, thus retracting the latch bolts in compartment C, permitting the roll top closure therein to move into closed position. In a similar manner current will flow from the battery 51 through the conductor 53, through conductor 58, through conductor 67, through one of the solenoids 49 in compartment D, through conductor 68, through conductor 96, through conductor 91, through the foot switch 72 in compartment A, through conductor 92, through conductor 97, through conductor 69, through the other solenoid 49 in compartment D, through conductor 70, and through the main line conductor 57, back to the battery, thus retracting the latch bolts in compartment D, permitting the roll top closure therein to move into closed position. It is thus seen that by simply operating the foot switch in compartment A, for example, closed circuit connections are made from the 130

battery 51 through each and all of the bolt retracting solenoids in each and every compartment. All of the roll top closures in all tellers' compartments can thus be closed simultaneously and immediately. In the same manner, by closing the foot switch in compartment B, or the foot switch in compartment C, or the foot switch in compartment D, the latch bolts in all compartments can be retracted and the roll top closure therein will immediately be moved into closed position. It is believed to be unnecessary to trace the various circuits from the battery through the various solenoids affected by closing the foot switch in compartment B, in compartment C, or in compartment D, since these circuits can be traced similarly to the circuits already traced in connection with the closing of the foot switch in compartment A.

20 It is now seen that we have provided a bank fixture readily adapted to replace the so-called cages generally in use in financial institutions. Our bank fixture occupies little space and can be variously designed to harmonize with the bank interior. The transverse partitions 14 need not be wider than the working counter 15. This permits the counter to be placed within a few feet of the bank wall and still leave room for a wide walk-way in the rear of the counters. It will be understood that we contemplate using our bank fixture not only in banks, but in any location where dealings are made and valuables passed over a counter. Wherever the word "bank" or "financial institution" appears in the specification or claims therefor, it will be understood that these terms are used to designate any place where our fixture herein described would be found convenient or desirable. Ample protection both to the teller and the securities and valuables of which he is in charge is provided for. The teller or bank operator can quickly and easily close his roll top closure whenever he desires to leave his position at the counter even for a moment. A temporary teller may then transact business at the vacated counter without danger of confusion or loss of articles. The roll top closure becomes automatically locked when once moved into closed position and cannot be opened without the aid of the proper key. No one can obtain access to the securities and valuables so enclosed upon the working counter without the authorized key, which the teller carries on his person. The teller can open his roll top closure with facility and ease by merely inserting his key into the lock, rotating the key through a small angle, and exerting a slight lifting movement on the lower edge bar 25 of the closure member. In addition, it is seen that we have provided a safety device by means of which any person not under the immediate control of robbers, for example, may release all of the roll top closures in all the tellers'

compartments and effect their automatic closing and locking. This operation can be performed with such facility and ease as to foil any robbing operations.

As many changes could be made in the above construction, and as many widely different embodiments of this invention may be made without departing from the scope thereof, it is intended that all matter contained in the above description or shown in the accompanying drawings shall be interpreted as illustrative and not in a limiting sense.

What we claim is:—

1. A bank fixture of the character described, including in combination, a teller's compartment having a shelf, a working counter spaced from said shelf, a roll top closure adapted to move between said shelf and said counter to enclose the space therebetween, said counter extending rearwardly of said enclosed space, means normally operative to move said closure into closed position, a device for releasably retaining said closure in open position, and electrical means for releasing said retaining device. 90

2. A bank fixture of the character described, including in combination, a teller's compartment having a shelf, a working counter spaced from said shelf, a roll top closure adapted to move between said shelf and said counter to enclose the space therebetween, said counter extending rearwardly of said enclosed space, means normally operative to move said closure into closed position, a spring pressed latch adapted to normally engage said closure to releasably retain the same in open position, and electrical means operative to retract said latch to permit said closure to move into closed position. 95

3. A bank fixture of the character described, including in combination, a teller's compartment having a shelf, a working counter spaced from said shelf, a roll top closure adapted to move between said shelf and said counter to enclose the space therebetween, said counter extending rearwardly of said enclosed space, a weighted device normally operative to move said closure into closed position, a spring pressed latch adapted to normally engage said closure to releasably retain the same in open position, and electrical means operative to retract said latch to permit said closure to move into closed position, said electrical means including a solenoid connected in electrical circuit with a power source. 110

4. A bank fixture of the character described, including in combination, a teller's compartment having a shelf, a working counter spaced from said shelf, a roll top closure adapted to move between said shelf and said counter to enclose the space therebetween, said counter extending rearwardly of said enclosed space, means normally operative to move said closure into closed position. 125

tion, a spring pressed latch positioned at each end of said closure operative to normally retain said closure in open position, and electrical means operative to retract both of said latches simultaneously to permit said closure to move into closed position.

5. A bank fixture of the character described, including in combination, a plurality of teller's compartments, each of said compartments having a shelf, a work counter spaced from said shelf, a roll top closure adapted to move between said shelf and said counter to enclose the space therebetween, said counter extending rearwardly of said enclosed space, means operative to move the closure into closed position, and means for releasably retaining the closure in open position, and electrical means whereby the retaining means for each closure may be released individually to permit any closure to move into closed position separately.

6. A bank fixture of the character described, including in combination, a plurality of teller's compartments, each of said compartments having a shelf, a work counter spaced from said shelf, a roll top closure adapted to move between said shelf and said counter to enclose the space therebetween, said counter extending rearwardly of said enclosed space, means operative to move the closure into closed position, and means for releasably retaining the closure in open position, and electrical means adapted to be operated from a remote point to retract all of said retaining means to permit all of said closures to move simultaneously into closed position.

7. A bank fixture of the character described, including in combination, a plurality of teller's compartments, each of said compartments having a shelf, a work counter spaced from said shelf, a roll top closure adapted to move between said shelf and said counter to enclose the space therebetween, said counter extending rearwardly of said enclosed space, means operative to move the closure into closed position, and means for releasably retaining the closure in open position, and a plurality of electrical devices located at a variety of remote points, each of said electrical devices being individually operative to retract all of said retaining means to permit all of said closures to move simultaneously into closed position.

8. A bank fixture of the character described, including in combination, a plurality of teller's compartments, each of said compartments having a shelf, a work counter spaced from said shelf, a roll top closure adapted to move between said shelf and said counter to enclose the space therebetween, said counter extending rearwardly of said enclosed space, means operative to move the closure into closed position, and means for releasably retaining the closure in open posi-

tion, and an electrical device conveniently located in each of said compartments, any one of said electrical devices being individually operative to simultaneously retract all of said retaining means to permit all of said closures to move into closed position.

9. A bank fixture of the character described, including in combination, a plurality of teller's compartments, each of said compartments having a shelf, a work counter spaced from said shelf, a roll top closure adapted to move between said shelf and said counter to enclose the space therebetween, said counter extending rearwardly of said enclosed space, means operative to move the closure into closed position, a latch for releasably retaining the closure in open position, and means within each compartment whereby the teller therein may retract said latch to permit the closure to move into closed position, and means adapted to be operated from a remote point to retract all of said latches to permit all of said closures to move into closed position.

10. A bank fixture of the character described, including in combination, a plurality of teller's compartments, each of said compartments having a shelf, a work counter spaced from said shelf, a roll top closure adapted to move between said shelf and said counter to enclose the space therebetween, said counter extending rearwardly of said enclosed space, means operative to move the closure into closed position, a latch for releasably retaining the closure in open position, and means within each compartment whereby the teller therein may retract said latch to permit the closure to move into closed position, and a plurality of electrical devices located at a variety of remote points, each of said electrical devices being individually operative to retract all of said latches to permit all of said closures to move simultaneously into closed position.

11. A bank fixture of the character described, including in combination, a plurality of teller's compartments, each of said compartments having a shelf, a work counter spaced from said shelf, a roll top closure adapted to move between said shelf and said counter to enclose the space therebetween, said counter extending rearwardly of said enclosed space, means operative to move the closure into closed position, a latch for releasably retaining the closure in open position, and means within each compartment whereby the teller therein may retract said latch to permit the closure to move into closed position, and an electrical device conveniently located within each of said compartments, any one of said electrical devices being individually operative to retract all of said latches to permit all of said closures to move into closed position.
